UNITED STATES PATENT OFFICE.

FRANK GRANT, OF WESTFIELD, MASSACHUSETTS.

DEVICE FOR TOILET USE.

1,187,423.

Specification of Letters Patent. Patented June 13, 1916.

Application filed November 30, 1915. Serial No. 64,267.

To all whom it may concern:

Be it known that I, FRANK GRANT, a citizen of the United States of America, and resident of Westfield, in the county of 5 Hampden and State of Massachusetts, have invented certain new and useful Improvements in Devices for Toilet Use, of which the following is a full, clear, and exact description.

10 This invention relates to a device for toilet use, such as a shaving brush, a tooth brush or other utensil or object, or both combined, and has for one of its objects to provide a casing or inclosure for the brush, or supplemental brush, or other object so that when not in use the same will be covered, but when in use the casing may serve as the handle by which the brush is held and manipulated.

Other objects of the invention will be 20 rendered apparent in conjunction with the description of the device and the manner of utilization of the same.

The invention is described in connection with the accompanying drawings and is set 25 forth in the claims.

In the drawings:—Figure 1 shows a longitudinal sectional view of a combined shaving brush and a casing therefor,—the brush being represented as being inclosed within 30 the casing at the time of disuse. Fig. 2 is a view similar to Fig. 1, but showing reversed relations of the parts so that the brush is distended and the casing available for use as a handle.

35 In the drawings, A represents a shaving brush having a circular shank B formed with a forwardly tapering portion *a* and also with a rearwardly tapering portion *b*.

C represents a cylindrical shell or casing 40 open at both ends and having the wall therein in near one end formed with a forwardly or outwardly beveled surface *d* and with a rearwardly or inwardly beveled surface *f*, for the engagement therewith of either of the inclined or tapered portions *b* or *a* of the brush accordingly as the latter is inclosed within 45 the casing as shown in Fig. 1, or by reversal, as shown in Fig. 2, is in its extended position for use.

50 The casing C is provided at different points in its length with perforations *g* which are inclined inwardly toward the end of the casing which is opposite said tapered surfaces *d* and *f*. These said perforations 55 are for the purpose of affording an access of air to the inclosed brush after having been

used and while more or less wet for the drying of the latter. Said perforations by having the inclinations as shown avoid the presence of sharp corners or shoulders 60 against which ends of the bristles of the shaving brush may engage when the latter is drawn out from the casing with the ends of the bristles foremost, such inclinations also preventing protrusion of the bristles 65 through the perforations.

When the shaving brush is inserted in the casing to the position shown in Fig. 1, the bristles are by the brush shank B with which they are connected drawn with their 70 free ends trailing so that the likelihood of their engaging in the perforations and becoming buckled is obviated. The brush shank B is provided with a short knob *h* which is of utility in drawing the shank 75 to its binding engagement in the internally tapered casing.

When the brush is to be inclosed it is inserted shank foremost in the right hand open end of the casing and moved so that 80 its beveled portion *b* is in engagement with the beveled portion *f* of the casing; the shank is then given an endwise draft and twist for perfecting the engagement between the surfaces *b* and *f* so that the brush is 85 firmly retained in its engagement in the casing.

When the shaving brush is to be displaced from the casing, endwise reversed and connected at the other end of the casing for use, 90 it is pushed out, preferably, through the medium of the knob *h* and brought to engagement, its tapered surface *a* having the pinching engagement in the beveled surface *d* at the mouth of the casing. 95

The shank B of the brush formed with reversed tapers *a*, *b*, as shown, is provided with lengthwise ranging channels *i* so that especially when the parts are in the positions and relations shown in Fig. 1, there 100 may be an entrance for air through the end of the casing and by way of such channels to the internal portion of the casing in which the bristles of the brush are inclosed for supplementing the means for drying out the brush. 105

The device described as apparent is convenient and desirable for one having occasion to travel frequently as the parts are susceptible of ready utilization and thereafter when carried in a suit case or traveling bag, the brush or brushes are practically 110

inclosed and the fact that the latter may be more or less wet is of no consequence or detriment.

I claim:—

- 5 1. A brush carrying member, including a shank of circular cross section, correspondingly forwardly and rearwardly tapered from its middle, and a cylindrical casing open at each end having the wall therein at 10 one end formed with correspondingly forwardly and rearwardly tapered portions for the engagement therewith of either of the inclined portions of the brush carrying member accordingly as the latter is inclosed 15 within the casing, or, by reversal, as in an extended position for use.
2. A brush carrying member including a shank of circular cross section, correspondingly forwardly and rearwardly tapered 20 from its middle, and a cylindrical casing open at each end having the wall therein at one end formed with correspondingly forwardly and rearwardly tapered portions, and provided at different points in its length 25 with perforations.
3. A brush carrying member, including a shank of circular cross section correspondingly forwardly and rearwardly tapered from its middle, and a cylindrical casing 30 open at each end having the wall therein at one end formed with correspondingly forwardly and rearwardly tapered portions

and provided at different points in its length removed from the said tapered portions with perforations which are inclined outwardly 35 toward the end of the casing having said tapered formations.

4. A brush carrying member, including a shank of circular cross section correspondingly formed forwardly and rearwardly 40 tapered from its middle, and provided with a knob or extension, and a cylindrical casing open at each end having the wall therein at one end formed with correspondingly forwardly and rearwardly tapered portions for 45 the purposes explained.

5. A brush carrying member, including a shank of circular cross section correspondingly forwardly and rearwardly tapered, and provided within the periphery of such 50 tapered portions with lengthwise ranging channels, and a cylindrical casing open at each end having the wall therein at one end formed with correspondingly forwardly and rearwardly tapered portions for the engagement therewith of either of the inclined portions of the brush carrying member.

Signed by me at Springfield, Mass., in presence of two subscribing witnesses.

FRANK GRANT.
